UNITED STATES PATENT OFFICE

DAVID N. IRWIN, OF DETROIT, MICHIGAN

AWNNG RAISING AND LOWERING DEVICE

Application filed February 4, 1928. Serial No. 251,903.

My invention relates to a new and useful improvement in an awning raising and lowering device adapted for use in the raising and lowering of awnings which are usually projected above and outwardly from window openings and the like.

It is an object of the present invention to provide a device of this class whereby the awning may be raised or lowered to any desired degree from the interior of the building.

It is another object of the invention to provide a device of this class which may be used disposed in either a horizontal or a vertical position without effecting the operation of the various parts.

It is another object of the invention to provide a device of this class which will be simple in structure, economical of manufacture and highly efficient in use.

Other objects will appear hereinafter.

The invention consists in the combination and arrangement of parts hereinafter described and claimed.

The invention will be best understood by a reference to the accompanying drawings which form a part of this specification and in which

Fig. 1 is a side elevational view of the invention disposed in horizontal position showing it applied.

Fig. 2 is a sectional view taken on substantially line 2-2 of Fig. 1 with parts broken away and parts shown in section.

Fig. 3 is a fragmentary view taken on line 3-3 of Fig. 2.

Fig. 4 is an end elevational view of the invention disposed in vertical form with a part broken away.

In the drawings I have illustrated the invention used on a structure having a wall 7 in which an opening 8 is formed for the reception of the window 9, over the upper end of which is disposed an awning which is mounted in the usual manner to swing downwardly and fold upwardly.

The invention comprises a U-shaped frame 11 which is suitably mounted on the exterior of the wall 7. The open end of the U-shaped frame 11 is closed by a rod 12, upon which is

rotatably mounted between the legs of the U-shaped frame a roller 13. Rotatably mounted in and extending between the legs of the U-shaped frame 11 is a rod or shaft 14, upon which is fixedly mounted a roller or spool 15 having at one end formed integral therewith the gear 16 adapted to mesh with the gear 17 which is formed integral with one end of the roller or spool 18 which is fixedly mounted upon the shaft 19. The gear 17 meshes with a gear 20 integrally formed on one end of the roller or spool 21 which is mounted fixedly on the shaft 22 which is rotatably disposed between and mounted on the legs of the U-shaped frame 11. A passage 23 is formed in one side of the roller 15, through which the cord or other flexible element can be projected and tied so that a rotating of the spool or roller 15 will effect a winding or unwinding of the cord or flexible element thereon. A similar passage 24 is formed in the spool or roller 18 and a similar passage 25 is formed in the spool or roller 21. Fixedly mounted upon the shaft 19, interiorly of the building, is a suitable crank 26 whereby this shaft may be rotated. Fixedly mounted upon the shaft 19 is a ratchet wheel 27 engageable with the dog 28 which is swingably mounted on the plate 29 which is mounted on the inner surface of the wall 7. Cords 30 and 31 and 32 are fastened to separate parts of the awning in a well known manner, and each of these cords is secured to one of the spools indicated, the number of spools being determined by the number of cords used for raising or lowering the awning. The number of cords will of course be determined to a large extent by the size and kind of awning with which used.

In operation it is but necessary for a person interiorly of the building to place the crank 26 on the rod 19, and by means of the set screw 33 bind the same thereon. A rotation of the rod 19 will effect the desired raising or lowering of the awning as the case may be.

As shown in Fig. 1 the device may be disposed in a horizontal position which may be inserted in some locations and on certain types of awnings.

In Fig. 4 I have illustrated that the device may be used equally well in a vertically extended position. In order to accommodate the device for use in a vertically extended position, the frame is made U-shaped and the connecting rod 12 and the roller 13 are of a less diameter than the width of the frame so that no interference is had with the cords when passing to or from the rollers or spools upon which wound or unwound.

The device is one which lends itself to a compact structure while at the same time affording an economical method of manufacturing a durable device of this kind.

While I have illustrated and described the preferred form of my invention, I do not wish to limit myself to the precise details of structure shown but desire to avail myself of such variations and modifications as come within the scope of the appended claims.

Having thus described my invention what I claim as new and desire to secure by Letters Patent is:

1. A device of the class described, comprising: a U-shaped frame; a plurality of spools rotatably mounted in said frame; a gear carried by each of said spools meshing with a gear carried by an adjacent spool; and means for rotating said spools.

2. A device of the class described, comprising: a U-shaped frame adapted for mounting on the exterior surface of a building wall; a plurality of rollers rotatably mounted on said frame; a gear carried by each of said rollers meshing with a gear carried on the adjacent roller; a shaft projected through said wall and connected to one of said rollers for effecting rotation of said roller in unison with rotation of said shaft; and means on the interior of said wall for effecting rotation of said shaft.

3. A device of the class described adapted for mounting on the exterior surface of a building wall comprising: a U-shaped frame; a plurality of rollers rotatably mounted in said frame; a shaft projected through one of said rollers and through said wall, said shaft being rotatable in unison with said roller; and a gear carried by each of said rollers meshing with a gear on the adjacent roller; and a crank on the inner end of said shaft for rotating the same.

4. A device of the class described adapted for mounting on the exterior surface of a building wall comprising: a U-shaped frame; a plurality of rollers rotatably mounted in said frame; a shaft projected through one of said rollers and through said wall, said shaft being rotatable in unison with said roller; a gear carried by each of said rollers meshing with a gear on the adjacent roller; a crank on the inner end of said shaft for rotating the same; and a ratchet and pawl on the inner surface of said wall for preventing reverse rotation of said shaft.

5. A device of the class described adapted for mounting on the exterior surface of a building wall comprising: a U-shaped frame; a plurality of rollers rotatably mounted in said frame; a shaft projected through one of said rollers and through said wall, said shaft being rotatable in unison with said roller; a gear carried by each of said rollers meshing with a gear on the adjacent roller; a crank on the inner end of said shaft for rotating the same; a rod connecting the legs of said frame at their ends; and a sleeve rotatably mounted on said rod between said legs.

In testimony whereof I have signed the foregoing specification.

DAVID N. IRWIN.
